GUSTAV DEEG, OF NEWARK, NEW JERSEY.

ELECTRIC DOOR-LOCK.

1,377,061.

Specification of Letters Patent.

Patented May 3, 1921.

Application filed February 27, 1920. Serial No. 361,797.

To all whom it may concern:

Be it known that I, GUSTAV DEEG, a citizen of the United States, and a resident of Newark, county of Essex, and State of New Jersey, have invented a new and Improved Electric Door-Lock, of which the following is a full, clear, and exact description.

This invention relates to door locks, and has reference more particularly to a door lock having mechanism operated by electricity so that the door may be locked from a distant point.

An object of this invention is to provide a door lock of the class indicated, which is adapted to prevent the exit of a thief from a bank, store, or other building by pressing an electric button at a distance from said door.

Another object of this invention is to provide a door lock which may be placed on the doors of private offices so that the door may be locked when desired by pressing an electric button located conveniently on the desk of the office.

Reference is to be had to the accompanying drawing forming a part of this specification in which it is understood that the drawing illustrates only one form of the invention, and in which—

Figure 1 is an elevation of an electric door lock with one of the cover plates removed to disclose the inner mechanism.

Fig. 2 is a view similar to Fig. 1 with the mechanism in an unlocked position.

Fig. 3 is a section on the line 3—3 of Fig. 1.

Fig. 4 is a section on the line 4—4 of Fig. 1.

Referring to the accompanying drawing by numerals, 10 indicates one wall of a flat box which is provided with three sides 11, and a fourth side 12 secured to the sides 11 and the wall 10, and extending somewhat beyond the sides 11 on each side of the box. A second wall 13 is secured to the box by means of screws not shown in the screw holes 14. An ordinary tumbler lock 15 is screwed into the wall 10 and is prevented from being unscrewed when the door is closed by means of a finger 16 which is provided on one end with a lug 17 adapted to engage a recess 18 formed in the lock 15. The end of the finger 16 opposite the lug 17 is screwed on to a threaded pin 19 which is slidably and rotatably mounted in a pair of guides 20. The end of the pin 19 op-

posite the finger 16 is provided with a head 21 in which is formed a screw driver slot 22 so that the pin 19 may be rotated and the position of the finger 16 relative to the recess 18 varied at will, thus allowing the lock 15 to be unscrewed and adjustment made on its interior mechanism.

A spindle 23 is also mounted in the guides 20 so as to be capable of axial movement substantially parallel to the upper side 11 of the box. A block 24 preferably square in cross section, is slidably mounted in a similarly shaped opening in the side 12, and is secured to one end of the spindle 23. This block 24 is provided with a bevel 25 which extends through the side wall and is customarily provided on door locks to engage a plate, not shown, on the jamb of the door and thus hold the door in a locked position. A lever 26 is fulcrumed on a pin 27, said pin being secured in the wall 10 of the box. One end of the lever 26 is positioned between a pair of pins 28 secured to the spindle 23 at right angles thereto. The other end of the lever 26 engages a lever 29 which is mounted on a square shaft 30 which extends laterally through the walls 10 and 13 of the box and is secured on the outside of said box to the door knob not shown. When the door knob is rotated either in clock-wise or counter clock-wise direction, the lever 29 will engage the lever 26 so as to move said lever 26 about the pin 27 to a position as shown in Fig. 2. When in this position, the lever 26 will have engaged the pins 28 so as to move the spindle 23 axially and thus withdraw the block 24 so that the door is free to swing open. A pin 31 similar to the pins 28 is secured at right angles to the spindle 23 and is adapted to limit the movement of the spindle 23 by engaging one of the guides 20. In order to resiliently hold the lever 26 so that the block 24 will extend through the side 12 and engage the plate on the jamb of the door, a spring 32 is secured to the lever 26 and to a pin 33, secured in the wall 10.

It is desired to provide a mechanism which will be operated by electricity and will prevent the axial movement of the block 24 into the interior of the box when an attempt is made to turn the knob of the door, and for this purpose a groove 34 is formed on the inner side of the block 24. An arm 35 is pivotally mounted at one end on the pin 27 and is provided on the other end with

a lug 36 which is adapted to engage the groove 34 and prevent the axial movement of the block 24. A lever 36' is secured to the arm 35 between the pin 27 and the lug 36, and extends obliquely to said arm 35 so that when the lever 36' is moved about the pin 27, the lug 36 will be disengaged from the groove 34 so as to allow the axial movement of the block 24 to the position shown in Fig. 10.2. The lug 36 is normally held in engagement with the groove 34 by means of a spring 37 secured to the lever 36' and to one side 11 of the box.

A barrel 38 is mounted in the lock 15 and is adapted to be rotated in said lock by means of a key on the outside of the door. A finger 39 is fixed to the inside end of the barrel 38 by means of screws 40 and when said finger 39 is rotated by means of a key to the position shown in dotted lines in Fig. 1, it engages the end of the lever 36' and rotates it slightly, so that the lug 36 is moved out of engagement with the groove 34 thus allowing the block 24 to be moved axially by rotating the door knob, and thus allowing the opening of the door. A lug 41 extends laterally from the lever 36 and is adapted to engage a shoulder 42 formed on an arm 43 which in turn is pivoted on a pin 44 secured to the wall 10 of the box. This shoulder 42 is adapted to normally hook over the lug 41 and hold the lever 36' in a position as shown in dotted lines in Fig. 1, so that the door will normally be unlocked and can be opened by rotating the knob thereof. The arm 43 is resiliently pressed against the lug 41 by a flat spring 45 secured to said arm 43 by means of a rivet 46, said spring pressing against the side 11 of the box. In order to electrically move the arm 43 about the pin 44 so as to disengage the shoulder 42 from the lug 41 and allow the lug 36 to engage the groove 34 under the action of the spring 37, a solenoid 47 is secured to the wall 10 by means of a bolt 48 so as to be positioned substantially at right angles to the arm 43. This solenoid 47 is provided with a soft iron core 49 which will be magnetized when an electric current is passed through said solenoid thus attracting the arm 43 and disengaging the shoulder 42 from the lug 41. An electric circuit 50 is connected to the solenoid 47 and includes a source of electric energy such as a battery 51 and a switch 52 which may take the form of an electric push button which can be located at any distant point. The door can also be locked by means of the key rotating the finger 39 until said finger engages an arm 53 secured to the arm 43 substantially at right angles thereto, so that the shoulder 42 will be disengaged from the lug 41.

In operation the door lock is installed on the door of a bank, store, a private office or the like, and the switch 52 is located at some

distant point from the door where it can be conveniently operated by a bank teller, a clerk, or a business man. In some establishment which handles valuables such as a bank or jewelry store, if a thief seizes some 70 of the valuables and starts for the door for the purpose of making his exit, the clerk or bank teller can press the button and the door will be electrically locked so that the exit of the thief is prevented, and his capture made 75 easier. When the electric button 52 is pressed, the lever 36' which has normally been positioned as shown in dotted lines in Fig. 1, is released since the arm 43 is attracted by the soft iron core 49 of the solenoid 47 so that the shoulder 42 is disengaged from the lug 41 thus allowing the lever 36' to move about the pin 27 under the action of the spring 37 until the lug 36 engages the groove 34, thus preventing the axial 85 movement of the block 24 by turning the door knob. Thus the exit of the thief is effectually stopped and his subsequent capture is made easier while he is likewise prevented from escaping with a quantity of 90 valuable goods. When it is desired to unlock the door after the button 52 has been pressed, a key is inserted in the barrel 38 and said barrel is rotated until the finger 39 engages the lever 36', thus causing the 95 shoulder 42 to engage the lug 41 and allowing the lever 26 to be moved about the pin 27 by means of the lever 29 on the knob shaft 30. When this lever 26 is moved about the pin 27 the block 24 will be moved 100 inwardly so that the mechanism will be positioned as shown in Fig. 2, and the door will be free to open. If it is desired to lock the door by means of the key, the rotation of the barrel 38 is continued so that the finger 105 39 engages the arm 53 thus causing the arm 43 to move about the pin 44 so that the shoulder 42 is disengaged from the lug 41, and the lug 36 then engages the groove 34 and prevents the opening of the door. 110

I would state in conclusion that while the illustrated example constitutes a practical embodiment of my invention, I do not limit myself strictly to the mechanical details herein illustrated, since manifestly the 115 same can be considerably varied without departure from the spirit of the invention as defined in the appended claims.

Having thus described my invention, I claim as new and desire to secure by Letters 120 Patent:

1. In a door lock, a sliding element associated with said door, a fixed member, said sliding element being adapted to move axially so as to engage said fixed member 125 and lock the door thereto, a door knob, means associated with said door knob for moving said slideable element axially so as to be disengaged from said fixed member, means released by electricity from a distant 130

point for preventing said sliding element from being disengaged from said fixed element by the door knob, and a lock coöperating with the electrical releasing means to 5 actuate said means and move it from engagement with the sliding element whereby the sliding element may be disengaged from the fixed element by the movement of the door knob.

10 2. In a door lock, a sliding element associated with said door, said sliding element being adapted to move axially so as to engage a fixed member, thus locking said door to said fixed member, a door knob, means 15 associated with said door knob for moving said sliding element axially so as to be disengaged from said fixed member, means released by electricity from a distant point for preventing said sliding element from being 20 disengaged from said fixed element by said door knob, and means operated by a key

for allowing the sliding element to be moved axially by said door knob.

3. In a door lock, a sliding element associated with said door, said sliding element 25 being adapted to move axially so as to engage a fixed member, thus locking said door to said fixed member, a door knob, means associated with said door knob for moving said sliding element axially so as to be disengaged from said fixed member, means released by electricity from a distant point for preventing said sliding element from being 30 disengaged from said fixed element by said door knob, means operated by a key for 35 allowing the sliding element to be moved axially by said door knob, and means operated by said key for preventing the axial movement of the sliding element by means of the door knob.

GUSTAV DEEG.
